UNITED STATES PATENT OFFICE.

ELROY A. CHASE, OF NORTHFIELD, VERMONT.

COARSE-GRINDING WHEEL FOR SURFACING STONE.

Application filed April 13, 1922. Serial No. 552,278.

To all whom it may concern:

Be it known that I, ELROY A. CHASE, a citizen of the United States, residing at Northfield, in the county of Washington and State of Vermont, have invented a new and useful Coarse-Grinding Wheel for Surfacing Stone, of which the following is a specification.

This invention relates to a grinding wheel 10 for surfacing stone and particularly for performing the first grinding operation on granite blocks or similar material having already an approximately plane surface, such as may be produced by my previously patented granite saw.

It is the general object of my invention to provide a grinding wheel for such purposes, which will quickly produce a smooth and even surface on the stone.

20 A further object is to provide a wheel which will effectively retain the grinding material on the grinding surface thereof, even when rotated beyond the edges of the work.

25 With these general objects in view, further features of my invention relate to details of construction by which increased wear of the wheel is obtained and which promote economical manufacture and efficient operation thereof.

30 My invention further relates to arrangements and combinations of parts which will be hereinafter described and more particularly pointed out in the appended claims.

35 A preferred form of my invention is shown in the drawings in which

Fig. 1 is a transverse sectional elevation of my improved wheel;

Fig. 2 is a bottom view thereof;

40 Fig. 3 is a perspective plan view of one of the grinding members;

Fig. 4 is an enlarged bottom view of a portion of one of the grinding members;

45 Fig. 5 is a detail sectional elevation, taken along the line 5—5 in Fig. 4;

Fig. 6 is a detail side elevation, looking in the direction of the arrow 6 in Fig. 4, and

Fig. 7 is a bottom view of a modification.

50 Referring to the drawings, I have shown a grinding wheel comprising a frame or plate 10, which may be in the form of a flat disc having a central opening 11 therein. A driving member 12 is secured to the

55 plate 10, said member having an upwardly

extending annular flange 13 and a head 14 connected to the member 12 within the central opening by inclined arms 15.

The arms 15 are set at such an angle that the leading edge of each arm is elevated, giving the arms a propeller-like action to feed downward the grinding material which is supplied through the central opening.

The driving head 14 is actuated by any suitable power mechanism (not shown) by which the wheel is continuously rotated, preferably with provision for additional bodily movement of the wheel relatively to the work.

The grinding surface of the wheel is 70 made up of a plurality of grinding members 16 (Fig. 3), each member being more or less in the form of a spiral and having lugs 17 on its upper surface threaded to receive bolts or screws 18 (Fig. 1) by which said members are attached to the frame 10. 75

The lugs 17 have two important advantages. The grinding members are commonly formed of cast iron and these lugs 17 may be easily surfaced off to provide a plane 80 surface to engage the frame or plate 10. Furthermore, the binding screws 18 need extend a less distance into the members 16 and the members in consequence can be used until they are largely ground away before 85 the ends of the screws 18 will appear on the grinding face.

In the preferred form of my construction, each grinding member 16 is provided with an outer face 20, inclined upwardly 90 and inwardly as shown in Fig. 5. As the inner face of each member is also disposed at the same general inclination, the thickness of the main section of each grinding member is substantially constant throughout its height. 95

The inner face of each member is serrated to provide a series of pockets 21 (Fig. 4) which extend diagonally downward and rearward toward the working face of the member. The outer walls 22 of these pockets are preferably formed substantially concentric with the axis of the wheel. 100

All of the grinding members on my improved wheel are preferably identical in size and shape, so that a wheel may be built up simply by securing the desired number of duplicate members 16 to the face of the frame or disc 10, as indicated in Figs. 1 and 2. 110

The grinding members are so disposed inwardly inclined toward the axis of said that the centrifugal force developed by the wheel and having serrated inner faces. 5 rotation of the wheel will work the grinding material gradually outward as the wheel 3. A grinding wheel comprising a frame, means by which said frame may be rotated, 65 revolves. The grinding material collects and a plurality of grinding members in the pockets 21, which slant rearwardly mounted on said frame, said members having a series of closely adjacent ledges on their inner faces extending the full height 70 and downwardly and thus deliver the material under the lower or working face of 75 the grinding member. As the material works out from under one grinding member, 10 it is immediately caught in the pockets of the next outward member and the feeding operation is repeated. 15 The pockets not only act to collect and feed the material under the grinding members, but also permit the wheel to be rotated beyond the edges of the work, as the grinding material is held in the pockets by the 20 centrifugal outward force and is thus largely retained on the wheel in position to resume cutting as soon as a particular portion of the wheel is again positioned over the work. This property of retaining the 25 grinding material is in itself a very important advantage of my invention, as it has been found impossible with the grinding wheels previously in use to retain the grinding material on the face of the wheel, if the 30 wheel was allowed to move beyond the edge. 16. A grinding wheel comprising a frame, means by which said frame may be rotated, and a plurality of grinding members mounted on said frame, said members comprising a series of obliquely disposed pockets 35 in their inner faces, with the outer wall of each pocket substantially concentric with the axis of said wheel. 17. A grinding wheel comprising a frame, means by which said frame may be rotated, and a plurality of grinding members mounted on said frame, said members comprising 40 a series of obliquely disposed pockets in their inner faces, with the outer wall of each pocket substantially concentric with the axis of said wheel. 18. A grinding wheel comprising a frame, means by which said frame may be rotated, and a plurality of grinding members mounted on said frame, said members comprising a series of obliquely disposed pockets 45 in their inner faces, with the outer wall of each pocket substantially concentric with the axis of said wheel. 19. A grinding wheel comprising a frame, means by which said frame may be rotated, and a plurality of grinding members mounted on said frame, said members comprising a series of obliquely disposed pockets 50 in their inner faces, with the outer wall of each pocket substantially concentric with the axis of said wheel. 20. A grinding wheel comprising a frame, means by which said frame may be rotated, and a plurality of grinding members mounted on said frame, said members comprising a series of obliquely disposed pockets 55 in their inner faces, with the outer wall of each pocket substantially concentric with the axis of said wheel.

The spiral grinding members shown in the drawings as covering somewhat less than a complete circumference, but the particular shape and extent of the grinding members may be considerably varied within the scope of my invention. 16. In Fig. 7, I have shown a modification in which a single grinding member 25 forms a continuous spiral on the face of the wheel. 40 The wheel is otherwise substantially similar to that already described. 17. Having thus described my invention and the advantages thereof, it will be evident that further changes and modifications can be made therein by those skilled in the art within the spirit and scope of my invention as set forth in the claims, and I do not wish to be otherwise limited to the details herein disclosed, but what I claim is:—

1. A grinding wheel comprising a frame, means by which said frame may be rotated, and a plurality of grinding members mounted on said frame, said members having a series of closely adjacent ledges on their inner faces and said ledges being upwardly and rearwardly inclined to form pockets for the grinding abrasive. 50
2. A grinding wheel comprising a frame, means by which said frame may be rotated, and a plurality of grinding members mounted on said frame, said members having continuous outer faces upwardly and

In testimony whereof I have hereunto affixed my signature.

ELROY A. CHASE.
